UNITED STATES PATENT OFFICE.

EDGAR ARTHUR ASHCROFT, OF LONDON, ENGLAND.

PROCESS OF PRODUCING NITROGEN AND REMOVING OXYGEN FROM MIXTURES OF GASES.

1,320,192.

Specification of Letters Patent.

Patented Oct. 28, 1919.

No Drawing.

Application filed June 6, 1918. Serial No. 238,612.

To all whom it may concern:

Be it known that I, EDGAR ARTHUR ASHCROFT, a subject of the King of Great Britain, residing at 65 London Wall, in the 5 city of London, and 4 Whitehall Court, Whitehall, in the county of London, England, have invented new and useful Processes of Producing Nitrogen and Removing Oxygen from Mixtures of Gases, of which 10 the following is a specification.

My invention relates to the manufacture of nitrogen and compounds of nitrogen and generally the removal of oxygen from mixtures of gases containing it and the obtaining 15 of useful products of, or resulting from, oxidation, and deoxidation, and consists in the employment, for such purposes, of a chemically reactive alloy of magnesium and lead, (including under magnesium any 20 suitable metal of the magnesium-calcium type and including under lead any metal of the lead-barium type).

The proportions of the constituent-metals 25 of the alloy which I have found to answer the purpose of my invention are from five per cent. to fifty per cent. of magnesium (or metal of the magnesium-calcium type) to from ninety-five per cent. to fifty per cent. of lead (or metal of the lead-barium type). 30 Usually an alloy containing about fifteen per cent. of magnesium to eighty-five per cent. of lead will answer best in the cold.

The invention may be carried out by passing 35 the gases containing oxygen, over, or through, the alloy which may be in any suitable condition, such as granular, or powdered, which will present sufficient surface to the gases. From the oxidized metal obtained by passing the gases containing 40 oxygen over, or through, the aforesaid alloy numerous products and useful effects can be obtained.

The conversion of the lead to PbO takes 45 place readily, on heating the mixture to about 400° centigrade in the presence of air. When however the more reactive lead hydroxid is desired this may be obtained by a longer exposure of the mixture in air, after damping with water, or by exposure in a very moist, or steamy, atmosphere. 50

The hydrates are extremely reactive substances and are obtained as aforesaid in a condition very suitable for subsequent further reactions. For many purposes the

mixture of hydrates of lead and magnesium may be used without separation. As an example of this procedure I mention the manufacture of lead peroxid which, according to the known reaction, may be easily 60 produced by passing chlorin gas into water in which is suspended a mixture of PbO_2H_2 and MgO_2H_2 in molecular proportions.

The oxidized alloys may also be employed for the preparation of any other lead salts, or compounds, and form in fact a most convenient base for this purpose. For instance a very fine quality of basic lead carbonate (white lead) may be obtained very easily by acting on the lead hydrate 65 with carbonic acid, either with, or without, separation of the magnesia. Litharge and minium may also be obtained from the material, of great purity and excellent physical properties by simple and economical 70 processes according to known practice or any suitable methods.

The mixture of oxids resulting from the oxidation of these alloys therefore forms 75 a most valuable starting point for many other manufactures and in numerous instances (such as lead peroxid and white lead) its use will constitute substantial improvements in the manufacture of these products. 85

In carrying out the invention in practice I may use for producing nitrogen, from atmospheric air for instance, an ordinary gas-holder with an open water tank and means for supporting and exposing the said 90 alloy in the gas space, the progress of the reactions being noted by the movements of the gas-holder. Or a smaller vessel may be used with means for exposing the alloy and gently circulating the mixed gases over 95 it by means of fans.

Ammonia may if desired be produced readily from the aforesaid alloys by acting on the heated powdered alloy with nitrogen gas forming nitrid and decomposing 100 the nitrid with steam in the known, or any suitable, manner.

What I claim is:—

1. A process involving the deoxidation of a gas, which comprises the step of bringing 105 the gas into contact with a chemically reactive alloy of metal of the magnesium-calcium type with metal of the lead-barium type.

2. A process involving the deoxidation of 110

a gas, which comprises the step of bringing the gas into contact with a chemically reactive alloy of magnesium and lead.

3. A process involving the deoxidation of 5 a gas, which comprises the step of bringing the gas into contact with a chemically reactive alloy of from five per cent. to fifty per cent. of metal of the magnesium-calcium type with ninety-five per cent. to fifty per

10 cent. of metal of the lead-barium type.

4. A process involving the deoxidation of 15 a gas, which comprises the step of bringing the gas into contact with a chemically reactive alloy of fifteen per cent. of metal of the magnesium-calcium type with eighty-five per cent. of metal of the lead-barium type.

5. A process involving the deoxidation of 20 a gas, which comprises the step of bringing the gas into contact with a chemically reactive alloy of five to fifty per cent. magnesium with ninety-five per cent. to fifty per cent. of lead.

6. A process involving the deoxidation of

a gas, which comprises the step of bringing 25 the gas into contact with a chemically reactive alloy of fifteen per cent. of magnesium with eighty-five per cent. of lead.

7. A process involving the deoxidation of 30 a gas which comprises the step of bringing the gas into contact with an alloy of magnesium and lead in the presence of water vapor.

8. A process involving the deoxidation of 35 a gas which comprises the step of bringing the gas into contact with an alloy of magnesium and lead in the presence of water vapor, said alloy comprising from five to fifty per cent. of magnesium, and from ninety-five to fifty per cent. of lead. 40

In testimony whereof I have signed my name to this specification in the presence of two subscribing witnesses.

EDGAR ARTHUR ASHCROFT.
